CLAIM

The ornamental design for a sensor device, as shown and described.

DESCRIPTION

FIG. 1 is a top view of a sensor device showing our new design;

FIG. 2 is a front top perspective view of the sensor device shown in FIG. 1;

FIG. 3 is a left side view of the sensor device shown in FIG. 1;

FIG. 4 is a front view of the sensor device as shown in FIG. 1;

FIG. 5 is a right side view of the sensor device shown in FIG. 1;

FIG. 6 is a rear view of the sensor device shown in FIG. 1;

FIG. 7 is a bottom view of the sensor device shown in FIG. 1; and,

FIG. 8 is a bottom rear perspective view of the sensor device shown in FIG. 1.

The broken lines shown in the figures are for illustrative purposes only and form no part of the claimed design.
